US0D1105098S

(12) **United States Design Patent** (10) Patent No.: **US D1,105,098 S**
 Amini et al. (45) Date of Patent: ** Dec. 9, 2025

(54) **ELECTRONIC DEVICE WITH GRAPHICAL USER INTERFACE**

- (71) Applicant: **Apple Inc.**, Cupertino, CA (US)
 (72) Inventors: **Mani Amini**, San Francisco, CA (US); **Patrick Lee Coffman**, San Francisco, CA (US); **Elizabeth Caroline Cranfill**, San Francisco, CA (US); **Vitalii Kramar**, Woodinville, WA (US); **Hoan K. Pham**, San Jose, CA (US); **Marcel van Os**, Santa Cruz, CA (US); **Eric Lance Wilson**, San Jose, CA (US)
 (73) Assignee: **Apple Inc.**, Cupertino, CA (US)
 (***) Term: **15 Years**
 (21) Appl. No.: **29/878,678**
 (22) Filed: **Jun. 26, 2023**

Related U.S. Application Data

- (63) Continuation of application No. 29/760,832, filed on Dec. 4, 2020, now Pat. No. Des. 994,682, which is a continuation of application No. 29/662,940, filed on Sep. 10, 2018, now Pat. No. Des. 904,451.
